UNITED STATES PATENT OFFICE.

JOHN ROGGINER, OF KANKAKEE, ILLINOIS, ASSIGNOR TO PARAMOUNT KNITTING COMPANY, OF CHICAGO, ILLINOIS, A CORPORATION OF ILLINOIS.

HOSIERY-FORM.

1,091,247.

Specification of Letters Patent. Patented Mar. 24, 1914.

Application filed July 23, 1906. Serial No. 327,363.

To all whom it may concern:

Be it known that I, JOHN ROGGINER, a citizen of the United States, residing at Kankakee, in the county of Kankakee and 5 State of Illinois, have invented certain new and useful Improvements in Hosiery-Forms, of which the following is a specification.

The general object of the present invention is to facilitate the handling of hosiery 10 after the same has been dyed and when it is to be stretched on a form and dried. The usual process consisting in stretching the hose in a dampened condition over a one-piece wooden form entails considerable loss 15 of time on account of the difficulty in drawing the damp material over the rigid form; besides subjecting the hosiery to excessive stretching both in placing the same on the form and in removing it therefrom. Furthermore, the removal of the stretched and 20 dried hosiery from the form is attended with considerable wrinkling of the hosiery which is inclined to spoil its shape and appearance. By the present invention it is 25 proposed to employ a collapsible form over which the hosiery can be placed without any fitting and stretching, the mere expansion of the form doing this work and the contraction thereof after the drying process 30 permitting the hosiery to be drawn off without any stretching or wrinkling.

With this object in view the invention consists in certain novel features of construction and combinations of parts the essential elements whereof are recited in the 35 appended claims and a preferred form of embodiment of which is illustrated in the accompanying drawings and fully described hereinafter.

40 Of said drawings, Figure 1 represents in side elevation a form constructed in accordance with the present invention, a sock being represented in section thereon and the form being shown expanded; and Fig. 2 45 represents the form in similar elevation but in collapsed condition, the sock being represented in section.

In the present instance a form is shown 50 designed for the handling of men's socks but it is to be understood that the invention is not confined to forms for use in this particular connection but may be availed of in the handling of various kinds of hosiery.

55 As here shown the form comprises a sole-

piece 2 whose end portions constitute parts of the toe and heel of the form; a leg and instep piece 3, one end of which constitutes part of the toe of the form; and another leg-piece 4, one end of which constitutes part of the heel of the form. These three pieces are in the form of comparatively narrow bars preferably of metal and are hinged together, the bars 2 and 3 being in the present case united by a pintle 5 at the point of the toe of the form and the bars 2 and 4 being similarly united by a pintle 6 at the point of the heel of the form, although any suitable hinge connection permitting a swinging hinged movement of the bars 3 and 4 upon the axes of the hinges at the extremities of the bar 2 may be employed.

The leg bars 3 and 4 of the form are united at their outer portions by a top bar 7 hinged to the bars 3 and 4 by pintles 8 and 9 and this top bar is preferably formed with a stop lug 10 produced by striking up a portion of the metal, which stop lug is designed to abut the inner edge of the bar 3 and limit the expansion of the form. 80

It will be seen that this construction provides not only for contracting the form throughout the forepart of the foot portion but also for contracting it between the heel portion and the instep portion. This latter 85 is of course the widest part of the hosiery form and it is the projection of the heel portion which gives the most trouble in the use of the wooden form. The above described construction entirely obviates any 90 difficulty in this regard because as clearly shown in Fig. 2 the form may be collapsed throughout its length including this troublesome heel portion so that the sock or stocking can be slipped over the same without any stretching whatever and of course removed with as great ease when the form is collapsed. Hence there need be no stretching of the ribbed top of a sock as necessarily takes place in the use of the 95 wooden form in getting this ribbed top past the heel portion of the form. Neither need there be any wrinkling of the hosiery in its removal from the collapsed form. Furthermore, the removal of the hosiery from the 100 forms can be very quickly accomplished so that no prolonged handling of hot forms is required.

105 It will thus be seen that the above described construction is well adapted to thor- 110

oughly accomplish the object primarily stated. At the same time it is to be understood that this construction is susceptible of modification without departing from the spirit and scope of the invention.

What is claimed is:

1. A collapsible hosiery form comprising a one-piece combined toe sole and heel piece extending from the toe to the point of the heel of the form, a one-piece combined leg instep and toe piece hinged to swing upon a fixed center at the toe end of the first-mentioned piece, and a one-piece combined leg and heel piece hinged to swing upon a fixed center at the point of the heel upon the end of said first-mentioned piece, said toe sole and heel piece and said leg and heel piece being arranged to collapse toward said leg instep and toe piece by the swinging movement of the first two-parts upon the axes of the hinges at the opposite ends of the toe sole and heel piece.
2. A collapsible hosiery form comprising a single combined toe, sole and heel piece, a single combined leg, instep and toe piece

hinged thereto at the toe end of the same, a single combined leg and heel piece hinged to the heel end of the first named piece and a top piece hinged to the leg ends of the other two pieces.

3. A collapsible hosiery form comprising a sole-piece, leg pieces hinged respectively to the toe and heel ends of the sole-piece, and a top piece hinged to the leg pieces and having a stop to limit expansion of the form.

4. A collapsible hosiery form comprising a combined toe, sole and heel piece, a combined leg, instep and toe piece hinged thereto at the toe end of the same, a combined leg and heel piece hinged to the heel end of the first named piece and a top piece hinged to the leg ends of the other two pieces and having a stop to abut one of the latter, substantially as and for the purpose described.

JOHN ROGGINER.
